SAFETY DEVICE

Charles E. Blank, Painted Post, N. Y., assignor to
Ingersoll-Rand Company, Jersey City, N. J., a
corporation of New Jersey

Application October 20, 1938, Serial No. 236,018

10 Claims. (Cl. 230—30)

This invention relates to a safety device for engine driven compressors and more particularly it relates to a device adapted to regulate the amount of fluid medium delivered to the engine and to act as a safety cut-off to prevent the delivery of any power medium to the engine under certain conditions.

The present device is adapted for use with a compressor unit which normally consists of a fluid compressor driven by an engine actuated by a power medium preferably steam. The device may be actuated by a fluid, such as oil from the engine lubricating system supplied thereto under pressure by either the lubricating pump or a separate oil pump. The apparatus may be employed to maintain the speed of the compressor unit constant regardless of the fluctuations of pressure in the power medium actuating the engine or of the pressure of the fluid in the receiver tank of the compressor.

Furthermore, the device is so arranged that should the oil pressure decrease for any reason, the steam supply to the engine is cut off to stop the operation of the unit until any defects may be ascertained and remedied.

In such an installation, two separate valves would ordinarily be furnished, one valve being employed to throttle the steam supply in accordance with the load demand and another valve to act independently of the first valve to stop the flow of power medium to the engine. Such an arrangement is subject to many disadvantages.

It is, accordingly, an object of the present invention to provide a device wherein the throttle valve and the cut-off valve are combined in one unit and inter-related in operation.

It is another object to provide a device wherein the power supply to the compressor unit may be cut off to stop operation of the unit.

A further object is to provide a device wherein the power medium may be throttled before being supplied to the engine save when the power medium supply has been cut off.

Still another object is to provide a simplified power medium throttle and cut-off device.

These and other objects will be apparent in the following description of which the drawings form a part.

Figure 1 is a front elevational view partially in section illustrating the device of the present invention.

Figure 2 is a side elevational view of the apparatus of Fig. 1 showing the throttle connections.

Figure 3 is a view in elevation of the opposite

or left-hand side of Fig. 1 showing the cut-off lever in its operating position and indicating the non-operating position of the lever in dash lines.

Figure 4 is a view in section of the mechanism for controlling the cut-off lever.

Figure 5 is a view in section of a throttle and cut-off valve of the present invention.

Figure 6 is a section taken along the line 6—6 of Fig. 5 illustrating the cut-off valve in its open position and the throttle in a throttling position.

Figure 7 is a section similar to Fig. 6 showing the cut-off valve in its cut-off position.

Figure 8 is a view in section of the apparatus for controlling the throttle portion of the valve.

With reference to Fig. 1, the device of the present invention consists of a valve body 1 having flanges adapted for connection to the power medium supply conduit 3 and the engine 5, as shown in Fig. 2. Mounted on one side of the valve body 1 is the plunger casing 7. Resting on the top of the plunger casing 7 is a weight 9 provided with a pin 11 on which is rotatably secured a rod 13. The rod 13 connects the weight 9 and the crank lever 15 which is secured to the shaft 17 by the key 19. If the weight 9 is raised, the rod 13 will raise the outer end of the crank 15, thus rotating shaft 17.

From the opposite side of the valve body 1 a shaft 21 extends to which is secured a cut-off lever 23 having a weight 25 at its free end. This cut-off lever will rotate the shaft 21 and thus control the cut-off portion of the valve. Ordinarily, the lever 23 is maintained by the trip lever 27 in the position indicated by the dash lines in Fig. 3.

The trip lever 27 has a notch 29 on which the bolt 26 of lever 23 rests. The lowermost or actuated position of the lever 23 is determined by the position of the stop 24. It is, of course, impossible to maintain the lever 23 in its upper position, unless the trip weight 33 is also maintained in its upper position, since the trip pin 35, extending from the trip weight 33, bears against the trip lever 27 as indicated in Fig. 1.

Assuming that the cut-off lever 23 is in its upper position and that trip weight 33 is in its upper position, it is readily seen that, should the trip weight 33 seek to reach its lower position, the trip pin 35 will strike the horizontal arm of the trip lever 27 and rotate the lever about its fulcrum 31 causing the supporting notch 29 to slip from beneath the trip lever bolt 26 and allow the weight 25 to move the trip lever 23 to its lowermost position.

The means for maintaining weight 33 in its

upper position are shown in section in Fig. 4 wherein it will be seen that the weight 33 has an extending arm 37 provided with a passage 39. In order to guide the movement of the extension 37, a guide casing 41 is provided which has a recess 43 and a passage 45 to receive the flange push button 47. This push button 47 is employed when the weight is being reset in its upper position before the engine has begun operating. When the push button 47 is moved into its left-hand position, the flange will extend into the passage 39 and maintain the weight in its upper position, thus providing a manual means for controlling the position of the weight 33. The automatic means consists of a diaphragm chamber casing 49 in which a diaphragm 51 is mounted. The diaphragm 51 divides the casing into two chambers 53 and 55. The chamber 53 is supplied with oil under pressure from the engine lubricating system by the conduit 57 opening thereinto.

Centrally located on the diaphragm and extending through a passage in the diaphragm casing 49 is a push rod 59. Any position assumed by the push rod 59 will, of course, depend upon the pressure of the oil in the chamber 53. As is shown, the push rod bears against a crank 61 fulcrumed at 63 and normally urged in a counter-clockwise direction by the spring 65 adjustably secured on the diaphragm casing 49.

The automatic means comes into operation to hold the trip weight 33 in its upper position when the engine is operating under normal conditions. Before starting the operation of the engine, as has been pointed out, the push button 47 is employed to maintain the weight in its upper position. As the engine is started and the speed of the engine increases, the oil pressure also increases and is supplied to the chamber 53 where it moves the diaphragm 55 towards the left until the push rod 59 moves the crank 61 and causes the automatic button 67 attached to the crank 61 to enter the passage 39 to hold the weight in its uppermost position. At the same time, the button 47 is pushed out of the passage 39 into recess 43. Should the pressure now decrease for any reason, the automatic button 67 will be moved toward the left out of the passage 39 and permit the weight 33 to drop. This movement occurs whenever the spring 65 is sufficiently strong to overcome the pressure of the oil in the chamber 53 bearing against the diaphragm 55 and thus the spring 65 determines the oil pressure at which the power medium is cut off.

As the weight 33 drops the trip lever 27, as has been explained, will be released and the cut-off portion of the valve will serve to stop the flow of power medium to the engine. In order to understand how the engine is throttled or the power medium to the engine cut-off during operation, it is necessary to refer to Fig. 5 illustrating the details of the valve. Valve body 1 has an inlet port 69 and an outlet port 71. Between these two ports is a chamber 73 wherein are located ported sleeves 75 and 77. The outer sleeve 75 is designed to throttle the power medium flowing through the valve and it is provided with ports 79 which communicate with the inlet port 69.

This sleeve 75 is rotatably mounted in the chamber 73 and is rotatably controlled by the shaft 17 which passes through the end of the sleeve and is fastened thereto by the nut 83. In order that the sleeve shall not move relative to the shaft 17 a flange 85 is provided on the shaft

which seats on the shoulder 87 provided on the sleeve. It is thus possible by tightening nut 83 to securely fasten the sleeve 75 to shaft 17. The sleeve and shaft are maintained in the valve by a bonnet 89 secured to the valve body 1 in any suitable manner and bearing against the flange 85. The shaft passes through this bonnet and leakage through the bonnet 89 around the shaft 17 is prevented by providing packing 91 maintained in position by the packing nut 93.

By threading the outer end of the shaft the crank lever 15 may be secured thereto in the manner about to be described. The end of the crank lever 15 is provided with a housing 95 secured thereto by the key 19. Fingers 97 extending from the bonnet 89 have a groove 99 in which the flange 100 of the housing rests. The flanges on the housing 95 do not extend completely around the housing since they are cut off as indicated in Fig. 2, one side being indicated by the dotted lines. In connecting the housing to the shaft it is apparent from Fig. 2 that, when the crank lever 15 is vertical, the fingers 97 permit the entrance of the housing and, upon rotation, the flange 100 will mesh with the grooves to hold the housing in position. Within the housing 95 is an adjustable nut 101 which is threaded on the shaft 17 and provided with spanner holes 103 in order that it may be turned to move the shaft 17 in or out of the valve. Obviously, when the sleeve is secured to the shaft, the turn of this adjusting nut 101 will move the sleeve longitudinally within the chamber 73 and in this manner the sleeve 75 may be held in any desired position against axial movement in recess 73. The other or cut-off sleeve 77 is rotatably mounted within the throttle sleeve 75 and is provided with inlet ports 105 normally communicating through the ports 79 with the inlet port 69 of the valve to permit power medium to pass within the sleeve 77. It also has outlet ports 107 opening into the exhaust passage 71 of the valve in order that the steam may pass from within the sleeve to the engine.

The sleeve 77 is maintained in the valve by the bonnet 109 holding the flange 111 in the groove 113 of the valve body. In this manner the sleeve 77 is held within the valve in such manner that it can only be rotatably moved. The means for rotating the sleeve consists of the cut-off lever shaft 21 to which the cut-off lever 23 is fastened by a pin 114. The portion of the shaft 21 engaging the sleeve 77 is fashioned with a square head 115 resting in socket 117 formed at the end of the sleeve. The shaft 21 is journaled in the bonnet 109 by the bearing 119 and the conical surface of the square head 115 of the shaft 21 is pressed against this bearing by the spring 121 placed in the socket recess 122. It will thus be seen that means have been provided whereby movement of the lever 23 will rotate shaft 21 and the sleeve 77.

In order to understand how the throttle portion of the valve operates, it is necessary to refer to Fig. 6 which shows the sleeve 75 in a throttling position while the sleeve 77 is maintained in its open position. Obviously, as the sleeve 75 is rotated in a clockwise direction, it will tend to cut down the size of the opening through sleeve 75 between the inlet passage 69 and the interior of sleeve 77. Conversely, when it is rotated in a counter-clockwise direction, it will open the ports of communication 79 through the sleeve 75 until the ports 79 and 105 in both

sleeves are concentric at which time the interior of sleeve 77 will be in open communication with the source of power medium supply.

What occurs when the trip lever has released the cut-off lever can be seen by Fig. 7. When this lever drops, it rotates the inner sleeve 77 until its ports 105 are completely out of engagement with the ports 79 of the outer sleeve 75. In this position it is obvious that no power medium can enter the inner sleeve 77 and flow through the exhaust port 71 to the engine. On assuming such a position, of course, the engine will be brought at a stand still and can only be started again by bringing these ports 105 back into engagement with the ports 79 by raising the cut-off lever 23 and its respective weight 25.

With respect to the throttle control apparatus illustrated in Fig. 8, it will be noted that it consists of a tubular plunger casing 7 through which extends a plunger 123. The lower end of the casing receives a bushing 125 in which is threaded an oil supply conduit 127 and by means of which oil pressure may be supplied to the bottom face 129 of the plunger 123. A washer 131 resting on a shoulder 132 is placed between the bushing 125 and the bottom face 129 of the plunger in order to secure one end of the spring 133 by means of pin 135.

The spring 133 extends through the bore 137 which passes through the entire length of the plunger 123 and is adapted to be secured at its opposite end on the lug 139 provided on the plug 141 which is threaded into the upper end of the plunger. To prevent any oil which might pass through the bore and escape from the plunger at the union of the plug 141 with the plunger 123 a sealing washer 142 is maintained therebetween. The weight 9 being furnished with a bore is adapted to fit around the plunger 123 and has a recess 143 in which the collar 145, surrounding the plunger 123, is placed. This collar is secured to the plunger by the pin 147.

When oil pressure is supplied through conduit 127 in sufficient degree to overcome tension of the spring 133 and the inertia of the weight 9, it will raise the plunger 123 and move the weight 9 away from the plunger casing 7. Since the pin 11 is carried on the weight and has a rod 13 connected thereto, the rising of the weight will rotate the crank lever 15 in a clockwise direction and thus rotate the throttle sleeve 75 to a throttling position. With this arrangement, as the speed of the engine increases, the oil pressure likewise increases and tends to move the weight upwardly so that, as the oil pressure increases, the throttle valve is moved closer to its closing position and thus tending to maintain the engine speed at a constant speed.

It will thus be seen that a device has been provided wherein the speed of the engine driving a compressor can be regulated by the degree of oil pressure on the engine. If, for any reason, the oil pressure increases, the engine will be throttled and, if the pressure continues to increase, the operation of the engine will automatically be stopped.

I claim:

1. In an engine driven compressor, the combination of a valve to control the flow of power medium to the engine in accordance with variations in the pressure of the oil in the engine lubricating system comprising a valve body having an inlet chamber and an outlet chamber, a rotatable outer sleeve in the valve body having ports through the walls thereof normally com-

municating with the inlet chamber, a second rotatable sleeve within the outer sleeve having ports through the walls thereof normally communicating with the outlet chamber and communicating through the outer sleeve ports with the inlet chamber, means responsive to said oil pressure to rotate the outer sleeve to limit the communication of the ports in said second sleeve with the inlet chamber and thereby throttle the flow of power medium to the outlet chamber, and a second means responsive to said oil pressure to rotate the second sleeve to move its ports out of communication with the inlet and outlet chambers to prevent flow of power medium therethrough upon a predetermined oil pressure drop.

2. In an engine driven compressor, the combination of a valve to control the flow of power medium to the engine in accordance with variations in the pressure of the oil in the engine lubricating system comprising a valve body having an inlet chamber and an outlet chamber, a rotatable outer sleeve between the inlet and outlet chambers having ports through the walls thereof, a second rotatable sleeve within the outer sleeve having ports through the walls thereof, means responsive to said oil pressure to normally maintain the ports in said second sleeve in open communication with the inlet and outlet chambers and adapted to prevent power medium flow through said ports upon rotation, and oil pressure responsive means to rotate the outer sleeve to move its ports into and out of registry with the inner sleeve ports to thereby throttle the fluid flowing from the inlet chamber to the outlet chamber.

3. In an engine driven compressor, the combination of a valve to control the flow of power medium to the engine in accordance with variations in the pressure of the oil in the engine lubricating system comprising a valve body having inlet and outlet chambers, a hollow rotatable means provided with ports normally in communication with the inlet chamber, a second hollow rotatable means provided with ports normally in communication with the outlet chamber and the inlet chamber through the ports of the first said means, means responsive to said oil pressure to rotate the first said means to throttle the flow of power medium to the second means and means to rotate the second means to prevent communication between the inlet and outlet chambers at a predetermined oil pressure.

4. In an engine driven compressor having an engine lubricating system, the combination of a valve to control the flow of power medium to the engine, a rotatable outer sleeve in the valve having ports enabling power medium to flow therethrough, a rotatable inner sleeve having its ports corresponding with the ports in the outer sleeve, means responsive to pressure variations in said lubricating system to rotate the outer sleeve to throttle the flow of power medium, and oil pressure responsive means to rotate the inner sleeve to prevent the flow of power medium.

5. In an engine driven compressor, the combination of a valve to control the flow of power medium to an engine in accordance with variations in the pressure of the oil in the engine lubricating system comprising a valve body having an inlet chamber and an outlet chamber, a rotatable outer sleeve between the inlet and outlet chambers provided with ports whereby fluid medium may flow from an inlet chamber to the outlet chamber, a second rotatable sleeve

within the outer sleeve having ports corresponding to and normally aligned with in said outer sleeve, oil pressure responsive means to rotate the outer sleeve to throttle the flow of power medium through the valve in accordance with an increase in the speed of the engine, and secondary oil pressure responsive means to rotate the second sleeve to prevent the flow of power medium through the valve when the oil pressure reaches a predetermined pressure.

6. In an engine driven compressor, the combination of a valve having inlet and outlet chambers to control the flow of power medium to the engine in accordance with variations in the pressure of the oil in the engine lubricating system, rotatable means interposed between the inlet and outlet chambers having ports opening into the inlet chamber, means to rotate the rotatable means, oil pressure operated means to actuate the last said means to throttle the flow of power medium from the inlet chamber, a second rotatable means within the first said means having ports adapted to co-act with the ports of the first rotatable means and to enable power medium to flow from the inlet chamber to the outlet chamber, means to rotate said second rotatable means to stop the flow of power medium from the inlet chamber to the outlet chamber, and oil pressure actuated means to normally prevent operation of the last said means.

7. In an engine driven compressor, the combination of a valve having inlet and outlet chambers to control the flow of power medium to the engine in accordance with variations in the pressure of the oil in the engine lubricating system, means interposed between the inlet and outlet chambers to throttle the flow of power medium to the engine, means within the first said means having ports to enable power medium to flow therethrough from the inlet chamber to the outlet chamber, means to rotate said second means to close said ports and to prevent the flow of power medium therethrough, and oil pressure actuated means to normally prevent operation of the last said means.

8. In an engine driven compressor, the combination of a valve having inlet and outlet chambers to control the flow of power medium to the engine in accordance with variations in the pres-

sure of the oil in the engine lubricating system, a rotatable sleeve having ports communicating with the engine, a shaft to rotate the sleeve, an oil pressure actuated plunger to control the shaft, levers connecting the shaft to the plunger, a second rotatable sleeve within the first said sleeve having ports to enable power medium to flow from the inlet chamber to the outlet chamber through the ports of the first said rotatable sleeve, means normally enabling power medium to flow through the ports of both said sleeves from the inlet chamber to the outlet chamber adapted upon rotation to prevent the flow of power medium, and oil pressure actuated means to control operation of the last said means.

9. In an engine driven compressor, the combination of a valve to control the flow of power medium to the engine in accordance with variations in the pressure in the oil lubricating system, a rotatably ported outer sleeve in the valve, a rotatably ported inner sleeve within the outer sleeve, a shaft to rotate the outer sleeve, an oil pressure actuated plunger to control the shaft, levers to connect the plunger and shaft, a square head shaft to rotate the inner sleeve, a weighted lever secured to said square head shaft, and an oil pressure actuated mechanism to normally maintain said square head shaft in one position and adapted to release said shaft when the fluid pressure decreases to rotate the inner sleeve to stop the flow of power medium to the engine.

10. In an engine driven compressor having an engine lubricating system, the combination of a valve having inlet and outlet chambers to control the flow of power medium to the engine, means interposed between the inlet and outlet chambers comprising a rotatably ported sleeve having ports opening into the inlet chambers, means to rotate the sleeve, a pressure actuated means to operate the last said means to throttle the flow of power medium from the inlet chamber in accordance with variations in pressure in said lubricating system, means within first said means normally enabling pressure medium to flow to the engine and adapted to stop the flow of pressure medium to the engine, and a lubricating oil pressure responsive means to normally render the last said means ineffective.

CHARLES E. BLANK.
